CONDITIONING CUTLERY SHARPENER

Cruz C. Renteria, Chicago, Ill.

Application April 12, 1952, Serial No. 282,063

8 Claims. (Cl. 51—276)

1

My invention relates to the conditioning of cutlery sharpeners, and more particularly, to the conditioning of razor strops and the like so as to impart to such conditioned strops uniquely advantageous properties for use in the sharpening of straight edge razors.

It is well known that after continued use razor strops tend to become decreasingly effective. The reasons for such decrease in effectiveness are believed to include accumulation of dirt and the like upon the strop, deformation of the normal strop surface structure, and various other factors which are not completely understood. Various methods and devices have been suggested for conditioning such strops so that their effectiveness is allegedly improved or substantially fully returned to their original effectiveness; but it has been found that most of such suggestions are defective or unsatisfactory for one reason or another.

At present, the most common practice among barbers and others who are vitally concerned with solving this problem involves the use of soap and water in more or less of a scrubbing and laundering operation. This procedure also has been found to have limited effectiveness. Other procedures using abrasives or the like have been found to cause too rapid wearing of the strops.

The instant invention provides for uniquely effective strop conditioning by the use of a particular combination of delicate controlled strop contact and the use of electrostatic lines of force and/or magnetic lines of force. In other words, the instant invention provides a unique means for conditioning a strop, employing electrostatic generation or induction, and also a unique means for employing in combination therewith magnetic lines of force.

It is, therefore, an important object of the instant invention to provide an improvement in the conditioning of cutlery sharpeners, in particular, the conditioning of razor strops.

It is a further object of the instant invention to provide an improved device for electrostatic generation for use in the conditioning of razor strops.

It is another object of the instant invention to provide an improved device for employing magnetic lines of force in the conditioning of a razor strop.

It is still a further object of the instant invention to provide an improved device for employing in combination electrostatically generated lines of force and magnetic lines of force in razor strop conditioning.

It is still another object of the instant invention to provide a device comprising an insulator frame, a flat conductor table-top therefor, a plurality of insulator guideways in said frame engaging said table-top, a reciprocal insulator car-

2

riage adapted to rubbingly engage a strop or the like to be conditioned mounted on said table-top, and insulator guide arms for said carriage slidably mounted in said guideways for electrostatic generation during carriage reciprocation. (As used herein, the terms "conductor" and "insulator" mean materials or structures which are electrical conductors or insulators, respectively.)

Other objects, features, and advantages of the present invention will become apparent to one skilled in the art from the following description of the embodiment illustrated in the accompanying drawings, in which:

Figure 1 is a side elevational view of a strop conditioning device embodying the instant invention;

Figure 2 is a top plan view of the device shown in Figure 1;

Figure 3 is an enlarged sectional elevational view taken substantially along the line III—III of Figure 1;

Figure 4 is an enlarged elevational view of the roll shown in Figure 3, with parts shown in section and parts broken away;

Figure 5 is an enlarged top plan view of the table-top plate of Figure 3, with parts broken away; and

Figure 6 is a sectional elevational detail view taken substantially along the line VI—VI of Figure 3.

As shown on the drawings:

The reference numeral 10 indicates generally a conditioning device for a strop conditioner adapted for use in the conditioning of a leather razor strop 11. The strop 11 has an elongated flat body portion to which is connected at one end a suitable handle 11a.

The strop conditioner 10 comprises a frame of wood or other suitable insulating material that 40 consists of two ends or cross pieces 12 and 13, each having a pair of integral legs 12a and 12b, and 13a and 13b, respectively, which contact a suitable surface upon which the device 10 is to be mounted. The end pieces or walls 12 and 13 extend upwardly in parallel generally vertical planes and have extending therebetween a vertical back wall 14 which extends between the back legs 12b and 13b and upwardly between the walls 12 and 13 to the same height as the walls 12 and 13.

Also, there is a horizontal lower shelf member 15 which extends forwardly from the back wall 14 between the end walls 12 and 13 the full width of the end walls just above the leg portions of each. The second or middle shelf 16, likewise, extends between the walls 12 and 13 in spaced horizontal substantially parallel relationship with respect to the lower shelf 15. The middle shelf 16, however, does not contact the back wall 14, but is spaced therefrom. It will thus be seen

that the strop conditioner 10 comprises a rigid supporting insulator frame comprising the side walls 12 and 13, the back wall 14 and the lower and middle shelves 15 and 16, which are secured together at their various points of contact by means of nails, screws, or the like. It will be appreciated, of course, that the insulator frame just described may also be formed of other suitable insulating materials such as synthetic resin plastics or plywood materials.

It will also be seen that the shelves 15 and 16 divide the frame into what constitutes a lower chamber A and an upper chamber B, the lower chamber A being defined by the shelves 15 and 16 in conjunction with the side walls 12 and 13 and the back wall 14, and the upper chamber B being an open topped chamber defined by the middle shelf 16, the back wall 14 and the side walls 12 and 13.

As shown best in Figure 3, the chamber A is provided with a flat piece of glass 17 which rests upon the lower shelf 15 and defines a floor for the chamber A. Also a second flat piece of glass 18 is secured to the bottom of the middle shelf 16 and, like the floor piece 17, extends the full width of the wooden shelf to which it is secured so as to define a ceiling for the chamber A. A back wall for the chamber A is provided by the vertical flat piece of glass 19 which, likewise, extends the full distance between the walls 12 and 13 and extends vertically from the top of the shelf 15 upwardly through the space between the back wall 14 and the middle shelf 16 to a short distance below the top of the back wall 14.

The floor and ceiling plates 17 and 18 of the chamber A engage the back glass wall 19, and also are preferably maintained in spaced relationship by means of spacers 20 and 21 (Fig. 1) which may be made of wood or glass and which extend substantially the full width of the walls 12 and 13 and lie closely adjacent to the walls 12 and 13, respectively. It will thus be seen that the flat glass pieces 17, 18 and 19 define a horizontal guideway extending longitudinally of the frame 10, for purposes which will be explained in detail hereinafter.

Referring now to the chamber B, as shown best also in Figure 3, it will be seen that a flat glass piece 22 of substantially the same size and shape as the glass pieces 17 and 18 is mounted upon the top side of the middle shelf 16 so as to define a glass floor for the chamber B. A vertically extending front wall 23, which is made of glass also, extends upwardly from the glass floor 22 to about one-half of the height of the chamber B and extends longitudinally thereof the full distance between the side walls 12 and 13.

As shown best in Figure 1, a pair of end walls 24 and 25 adjacent the side walls 12 and 13, respectively, extend upwardly from the glass floor 22 between the back wall 19 and the front wall 23 to the full height of the back wall 19. The lower portion of the chamber B, which extends to the height of the front wall 23 is filled with rosin 26 which is poured or cast into that portion of the chamber B and allowed to set therein so as to define a generally flat rectangularly cross-sectioned cake of rosin.

The top of the chamber B is defined by a table-top assembly indicated generally by the reference numeral 27. As will be seen from Figures 1, 2, and 3, the table-top assembly 27 rests upon the top edges of the back glass wall 19 and the short end glass walls 24 and 25 defining the chamber B, and the top surface of the table-top assembly

is flush with the top edges of the frame back wall 14 and the frame side walls 12 and 13.

As best seen in Figures 3 and 5, the table-top assembly 27 comprises a flat generally rectangular top plate 28 and a similarly shaped bottom plate 29, each of which is made of a suitable conductor such as aluminum or any other suitable metal conductor. The top and bottom plates 28 and 29, respectively, extend in spaced parallel relationship from the back frame wall 14 to the front edge of the side walls 12 and 13 and the full longitudinal distance of the frame between the side or end walls 12 and 13.

Sandwiched between the top and bottom plates 28 and 29, respectively, is a rosin layer 30, which comprises a relatively thin sheet or slab of cast rosin or the like fusible thermoplastic insulator material having embedded therein finely divided particles of magnetic iron. Preferably, the magnetic iron is the so-called "magnetic dust" obtained by pulverizing or grinding a permanent iron magnet or load stone. The magnetic dust is embedded in the rosin matrix forming the layer 30 so as to define an insulator layer having variable magnetic properties. In other words, the magnetic iron particles impart magnetic properties to the entire layer 30, but such magnetic properties may be altered by exposure of the layer 30 to another suitable source of magnetic lines of force, such as a permanent magnet. The table-top assembly is preferably held together by a plurality of nut and bolt assemblies 31, which pass through apertures, such as at 32 (Fig. 5) in the lower plate 29, and which have screw heads counter-sunk in the upper plate 28 to present a top smooth surface, as is well known in the art.

It will thus be seen that the instant conditioner is provided with an internal glass frame, wherein there is glass-to-glass contact between each of the various glass plate members thereof, which include the plates 17, 18, 19, 22, 23, 24 and 25, as well as the spacers 20 and 21, if such are glass. As will be pointed out hereinafter, the purpose of the inner glass frame just described is for use in electrostatic generation, and it will be appreciated that other insulators similarly responsive in electrostatic induction processes may be employed in place of the glass. In fact, it is preferable to employ rosin, as in the layer 26, to provide at least one such guideway.

I have found, however, that the results obtained in the practice of my invention are consistently superior using the instant glass structure with only the one rosin surface, and glass is therefore preferred for use in the instant invention in the inner frame work as just described.

Referring again to Figure 3, it will be seen that the frame 10 mounts a reciprocal carriage assembly designated generally by the reference numeral 31. The assembly 31 comprises a manually graspable means or handle 32 extending vertically upwardly from an integral flattened insulator head portion 33 preferably of wood, which presents a bottom rubbing face 33a that lies laterally of the strop 11 upon the top surface thereof for rubbingly engaging the same during carriage reciprocation.

The head portion 33 is wrapped by a supporting band, such as the wire 34, which supporting band may be employed to affix the head portion 33 to the top of a vertically extending-brass mounting arm 35. If preferred, the mounting arm 35 may be secured to the head portion 33 by other means, of course, the main object being to provide a rigid structure whereby the head por-

tion 33 extends horizontally and the vertical movement thereof is controlled by vertical movement of the arm 35. The arm 35 extends downwardly to be engaged by a sleeve 36, wherein there is mounted a wing bolt 37 to provide for adjustable mounting of the arm 35 in the sleeve 36, as is well understood.

The sleeve 36 is fixedly mounted on a carriage guide or frame 38, comprising a vertically extending body piece 38a which mounts the sleeve 36 and lies closely adjacent the arm 35, and an upper 38b and a lower 38c guide arm extending into said frame 19 from the upper and lower extremities, respectively, of the guide body 38a.

As will be seen from Figure 3, the lower guide arm 38c extends into the lower chamber A, substantially the full lateral dimension or width thereof; and the arm 38c is wrapped by an insulator fabric-like material, preferably a fur 39, which completely insulates the brass arm 38c from the glass pieces 17, 18, 19, 20 and 21 in the chamber A. It will thus be seen that reciprocation of the carriage assembly 31 causes guided sliding engagement between the fur-wrapped arm 38c and the glass in the chamber A, thereby generating static electricity.

Although the precise phenomena involved in obtaining the uniquely advantageous results which are obtained in the practice of my invention cannot be fully understood, because such are essentially electrical phenomena, I have come to certain conclusions which I wish to submit for the benefit of those skilled in the art, but by which it will be understood I am not to be bound. For example, it is understood that so-called "frictional" electricity or static electricity may be generated by rubbing glass with fur, in which case the glass assumes a positive charge and the fur becomes negatively charged. It is also known that conductors such as the metals including brass and aluminum may become charged with static electricity, for example, by contacting the same with one of the insulators such as glass or fur that is employed in an electrostatic induction or generation operation such as that just described.

It is also a fundamental rule of electrostatic generation that the generation of a given positive or negative charge at one extremity of an insulator has the effect of inducing an opposite charge at the opposite end thereof, whereas a conductor in contact with one or the other of such ends is charged the same as the end of the insulator with which it is in contact.

Although there have been occasional suggestions concerning the use of rubbing of a material such as a razor strop so as to induce static electricity by such rubbing, such procedures would be unsatisfactory in that the rubbing itself must necessarily involve severe abrasive action with respect to the strop, whereas in my invention, I may use controlled contact and rubbing to precisely the extent desired and also I may effect electrostatic generation involving the generation of substantially greater electrostatic potential by means of rubbing engagement which does not involve abrasive action upon the strop itself and which does involve the use of materials best suited for electrostatic generation.

In addition, I have found that there is a certain amount of current leakage through the strop. Such current leakage would, of course, effectively induce a new magnetic field in the layer 30 and this newly induced magnetic field, presumably effectively creates lines of force which

pass through the leather strop. It is now my belief that the unique cooperation between the electrostatic forces and the magnetic forces, conceivably also in addition to the forces created by current leakage through the leather strop, bring about the entirely new and greatly improved strop conditioning effect which I obtain in the practice of my invention. The peculiar cooperation between these various energy sources or lines of force is not completely understood, but it has been found that by the use of both of the sources of lines of force (electrostatic as well as magnetic) herein described, I am able to obtain results substantially superior to those obtained by the use of only one of such sources. The use of either one alone, however, produces good results in the practice of the instant invention.

Referring again to Figure 3, it will be seen that the top guide arm 38b extending inwardly from the upper extremity of the guide body 38a also has a fur or wool wrap 40 thereabout so as to effectively insulate the same against contact with the top surface of the rosin cake 26 as well as the various glass plates 23, 24, 25 and 19. It will thus be seen that the guide member 38 effectively guides the movement of the carriage assembly 31 and also by virtue of the sliding engagement of such wrapped guide member 38 affords means for electrostatic generation.

Referring now to Figure 6, it will be seen that the carriage base 33 has affixed at the bottom thereof a relatively soft resilient rubber-like fabric wrap 41 which forms an outside layer, the bottom of which constituting the bottom face 33a of the base, hereinbefore mentioned. This resilient cloth wrap 41 is adapted to smoothly and unabrasively engage the razor strop 11 so as to make light rubbing contact therewith.

Preferably, the fabric wrap 41 covers a layer 42, which in turn is wrapped about a permanent magnet 43 securely affixed to the bottom portion of the base 33 and extending the full width thereof. The inner wrap 42 is preferably composed of a flexible material such as a rubberized fabric having impregnated therein iron particles such as magnetic dust, hereinbefore described. In general, the cooperation between the members 42 and 43 is such that a magnetic field is maintained thereby, the outer wrap 41 serving, among other things, as an insulator, and being securely clamped to the base 33, as by means of the wire loop 34 (as shown in Figure 6).

It will thus be seen that the instant invention provides for the use of means for conditioning a razor strop which necessitate the minimum controlled wear and tear on the strop and the use of lines of force (magnetic as well as electrostatic) through means which are not directly involved in the rubbing or abrasive contact between the carriage assembly 31 and the strop 11.

In addition, I have found that rubbing contact between the strop and the carriage member can be reduced to a substantial minimum by the use of a roller 44 (Fig. 4) as a substitute for the fabric wrap 41 and magnet members 42 and 43 wrapped thereby. As will be seen from Figure 4, the roller 44 comprises an inner brass or suitable rigid metal roll 45 suitably equipped with stub shafts 46, 46 that the roll may be mounted for rotation as is well understood in the art, an inner sleeve layer 47 wrapped about and encasing the brass roll 45 and an insulator rubberized fabric wrap 48 therefor. The sleeve layer 47 is preferably composed of rosin or fabric or the like insulator having embedded therein mag-

netic dust, as hereinbefore described, so that the layer 47 is also capable of providing variable magnetic lines of force. The roller 44 may be mounted rotatably upon the head portion 33 so as to operate in place of the magnet members 42 and 43 and their fabric wrap 41, or the roller 44 may be used in conjunction with a permanent magnet, such as 43, mounted in the head portion 33 above the roller 44.

Also, the roller 44 may be mounted rotatably, as on the arms 49 shown in Figure 3 mounted on the top guide arm 38b. The roller 44 thus positioned assists in the guiding function by contacting the table-top 27 and may assist in electrostatic generation by such contact. In addition, the roller 44 presents an additional source for the formation of magnetic lines of force.

As another advantageous aspect of the instant device, I should like to point out that the instant device may also be used to condition the so-called "Butcher's steel" or honing device for sharpening cutlery. In this use the operation is the same except that the honing instrument replaces the leather razor strop, the conditioning being most advantageously effected presumably because of the presence of the magnetic lines of force.

It will, of course, be understood that certain of the various foregoing details of structure and operation herein set forth relate specifically to the instant example described herein, and various of such details may be varied through a wide range without departing from the principles of this invention; and it is not, therefore, the purpose to limit the patent granted hereon otherwise than necessitated by the scope of the appended claims.

I claim as my invention:

1. A device of the class described comprising an insulator frame, a flat conductor table-top therefor, a plurality of insulator guideways in said frame engaging said table-top, a reciprocatable insulator carriage adapted to rubbingly engage a strop or the like to be conditioned mounted on said table-top, and insulator guide arms for said carriage slidably mounted in said guideways for electrostatic generation during carriage reciprocation.

2. A device of the class described comprising a stationary wooden frame, an elongated flat aluminum table-top mounted thereon for receiving and supporting a strop to be conditioned, a glass guideway mounted in said frame longitudinally of said table-top and engaging the same from beneath, a reciprocatable brass carriage frame, a fur-covered arm on said carriage frame slidably engaging said guideway for electrostatic generation during carriage reciprocation, and an insulator fabric mounted on said carriage frame for rubbing contact with the strop during carriage reciprocation.

3. A device of the class described comprising an insulator frame, a flat conductor table-top therefor to receive a strop or the like, said table-top comprising a magnetizable layer of magnetic iron particles finely dispersed in an insulator rosin matrix sandwiched between conductor plates, a plurality of insulator guideways in said frame engaging said table-top, a reciprocatable insulator carriage adapted to rubbingly engage a strop or the like to be conditioned and mounted on said table-top and insulator guide arms for said carriage slidably mounted in said guideways for electrostatic induction during carriage reciprocation.

4. A device of the class described comprising an insulator frame, a flat conductor table-top therefor to receive a strop or the like, said table-top comprising a magnetizable layer of magnetic iron particles finely dispersed in an insulator rosin matrix sandwiched between conductor plates, a plurality of glass guideways mounted in said frame and engaging said table-top, at least one of said glass guideways having mounted thereon as a guiding surface component a layer of rosin, a reciprocatable insulator carriage adapted to engage a strop or the like mounted on said table-top, and insulator guide arms for said carriage slidably mounted in said guideways.

5. A device of the class described comprising an insulator frame, a flat conductor table-top therefor to receive a strop or the like, said table-top comprising a magnetizable layer of magnetic iron particles finely dispersed in an insulator rosin matrix sandwiched between conductor plates, a plurality of guideways in said frame, a carriage mounted for reciprocal movement in said guideways, and a magnet mounted in said carriage and adapted to be positioned close to but insulated from the strop during rubbing contact between the carriage and the strop.

6. A device of the class described, comprising an insulator frame, a flat conductor table-top therefor to receive a strop or the like, said table-top comprising a magnetizable layer of magnetic iron particles finely dispersed in an insulator rosin matrix sandwiched between conductor plates, a plurality of guideways in said frame, a carriage mounted for reciprocal movement in said guideways, and an insulator member mounted on said carriage for rubbing contact with the strop during carriage reciprocation, said insulator member comprising an insulator fabric wrap and an inner magnetizable layer of magnetic iron particles finely dispersed in an insulator matrix wrapped by said insulator fabric.

7. A device of the class described, comprising a stationary wooden frame, an elongated flat aluminum table-top mounted thereon for receiving and supporting a strop to be conditioned, a plurality of glass guideways mounted in said frame longitudinally of said table-top and engaging the same from beneath, a reciprocatable brass carriage frame, a plurality of fur-covered arms on said carriage frame slidably engaging said guideway for electrostatic generation during carriage reciprocation, and a rosin slab interposed between at least one of said fur-covered carriage arms and the glass guideway adjacent thereto.

8. A device of the class described, comprising a stationary wooden frame, a flat conductor table-top therefor to receive a strop or the like, said table-top comprising a magnetizable layer of magnetic iron particles finely dispersed in an insulator rosin matrix sandwiched between a pair of flat elongated aluminum plates, a plurality of glass guideways mounted in said frame longitudinally of said table-top having glass-to-glass contact therebetween and having glass-to-aluminum contact, a reciprocable insulator carriage adapted to engage a strop or the like mounted on said table-top, and insulator guide arms for said carriage slidably mounted in said guideways.

CRUZ C. RENTERIA.
